Fig. 9.

INVENTOR.
John Szako

UNITED STATES PATENT OFFICE.

JOHN SZAKO, OF NEW YORK, N. Y.

PLANE.

Application filed April 4, 1924. Serial No. 704,160.

To all whom it may concern:

Be it known that I, JOHN SZAKO, a citizen of the United States, and resident of 362 West 42d Street, New York, in the county of New York and State of New York, have invented certain new and useful Improvements in Planes, of which the following is a specification.

This invention relates to improvements in 10 woodworking planes, particularly rabbet planes of the type commonly termed filister planes, especially well adapted for cross-grain planing, and it is the principal object of my invention to provide a plane of 15 this type with novel means for ensuring at all times an accurate working with or against the grain.

Another object of the invention is the provision of a plane of this character having 20 a single side wall with adjustable gages for adjusting the plane and supporting the same with reference to the work-piece operated upon.

A further object of the invention is the provision of a plane having an auxiliary, 25 movable and adjustable base for the convenient removal of the chips.

A still further object of my invention is the provision of a plane of this type 30 equipped with novel and improved means for holding and guiding the cutter blade on its bed for allowing a ready adjustment of the same, and a locking of the parts in their adjusted positions.

It is furthermore, also an object of the invention to provide a plane with means for 35 permitting a limited lateral adjustment of the cutter and with means for regulating the tension of the engagement between blade and bed and for locking these parts in their adjusted positions.

These and other objects of my invention will become more fully known as the description thereof proceeds and will then be specifically pointed out in the appended claims.

In the accompanying drawings, forming a material part of this disclosure:

Figure 1 is a side elevation of a plane constructed according to my invention.

Figure 2 is a rear end view of the plane

looking in the direction of arrows 2—2 of Figure 1.

Figure 3 is a front end view of the plane looking in the direction of the arrows 3—3 of Figure 1.

Figure 4 is a view of the cutter seen along line 4—4 of Figure 1.

Figure 5 is a cross-section on line 5—5 of Figure 1.

Figure 6 is a longitudinal sectional view 60 of the plane.

Figures 7 and 8 are detail side and end views of a pawl and its finger.

Figure 9 is a detail elevation of an adjusting and locking bolt.

The body of the plane has only one single side wall or upright 10, the foot of which is secured to the rear base plate 11 by a dovetail or morticed connection 13, and by a similar connection 13' to the front base 70 plate 12.

An auxiliary, movable base plate 14 is slidably mounted on plate 12, and carries near its outer end a post 15 through a smooth bore of which an adjusting screw 16 works 75 loosely which engages with its threaded rear end a bore 17 provided with interior thread in a post 18 on the stationary base 12.

A suitable, preferably hollow handle or grip member 19 is secured to the rear end 80 of the base plate 11, provided for this purpose with a suitable boss, by means of a screw bolt 20 or the like.

Bosses 21 and 22 on the base plates 11 and 12 carry curved arms 23 and 24, the 85 outer ends of which are connected by a side handle bar 25.

In the bosses 21 and 22 are also secured, below the arms 23 and 24, rods 26 and 27 to the outer ends of which brackets 28 and 29 90 are attached provided with heel pieces 30 and 31 or the like to which is attached a gage 32 adapted to engage the side of the work piece for guiding the longitudinal movement of the plane. A depth gage 33 is 95 adjustably attached to the side wall 10 by the set screws 36 and 37, the shanks of which extend through elongated slots 34 and 35 in the upright arms of the gage, whereby the gage may be vertically adjusted to engage 100

the top side of the work piece to regulate the depth of the cut. The lower engaging flange 38 of the gage 33 is somewhat outwardly flared, to ensure a perfect engagement with the work piece.

In order to cut the edge of the rabbet made by the plane perfectly and accurately smooth, a roller cutter 39 is laterally disposed on the plane being mounted on a stub shaft 40 (Fig. 5) which is secured in a block 41 set in an opening of the side wall 10 and adjustable therein within certain limits by means of a set screw 42 equipped with a knurled head 43.

A cutter bed 44 is secured to the side wall 10 and is adapted to carry the cutter blade 45 having a lower oblique cutting edge 46 working in a similarly shaped cross-slot 47 in the base plate. In its body, the blade 45 is provided with a longitudinal T-slot 48 allowing the passage of a knurled knob or head 49 through the head of the T-slot which is attached to the upper end of an adjusting screw 50 working in bed 44, and allowing a limited adjustment of the cutter blade by the engagement of the head 49 with the walls of the slot in the blade.

A guard or guide plate 51 is adapted to rest on top of the cutter blade 45 to hold the same against its bed 44 and is connected with the cutter 45 by means of a screw 52, the head of which is located in a recess 53 of the bed 44 and accessible for adjustment by hand.

The pressure of the guard plate 51 upon the cutter blade can be regulated by means of a substantially convex shaped spring clamping plate 54, having its peripheral edge engaging the upper face of the guard 51 and provided with a perforated boss 55 in its center with a threaded inner wall in the perforation for engagement by the threaded part of a bolt 56. The head 57 of the bolt rests upon plate 54, while its shank 56 extends through the plate 51, cutter 45 and bed 44. The lower end of the shank 56 is provided with a slot 58, adapted to receive the finger 59 attached as at 60, to the pawl 61 for locking the end of the bolt 56 in its adjusted position. The pawl 60 is pivotally attached to the bed 44, by brackets 60', whereby the pawl may be rocked to bring the finger into engagement with the slot 58.

A limited lateral adjustment of the cutter blade is made possible by the provision of an adjusting screw 63 having a knurled head 64 and working with its inner end in a block 65 guided within the lower part of slot 48.

The operation of my device will be entirely clear from the above description. After the proper adjustment of gage 33 to engage the top of the work piece with its flange 38 for regulating the desired depth of the cut, and after adjustment of the gage 32 to act as a fence, the plane is ready for

operation. Chips clogging the rabbet and the slot in the base are conveniently and quickly removed by the proper removal of the auxiliary base 14 while the edges of the groove made in the work-piece are smoothed by the cutter roller 39 which will also prevent the work piece from splitting and splintering particularly when working across the grain; if desired the cutter can be laterally adjusted by the proper operation of screw 63 within certain limits, and the tension of the engagement between cutter blade and its bed can be properly regulated by the operation of bolt 56 which is then locked in adjusted position by the proper operation of the pawl 61 to bring its finger 59 into engagement with the slot 58 of bolt 56.

It will be clear that the construction shown may be modified in various ways as fall within the scope of the appended claims without deviation from the principle and spirit of my invention.

What I claim as new, and desire to protect by Letters Patent is:—

1. A bench plane bit clamping means comprising a blade, a spring plate, having a screw-threaded boss in the center thereof, a locking bolt having a threaded portion engaging the threads of said boss, and a lower apertured end extending through said bed, a pawl pivoted on said bed and a finger on said pawl adapted to engage the apertured end of said locking bolt for locking the parts in their adjusted positions.

2. A bench plane bit clamping means comprising a bed, a blade, a spring plate, a bolt extending through said plate, blade and bed, having a slot in its lower end, and means carried by said bed adapted to engage the slot of said bolt for locking the parts in position.

3. A bench plane bit clamping means comprising a bed, a blade, a spring plate, a bolt extending through said plate, blade and bed, having a slot in its lower end, and a pawl pivoted on the under side of said bed adapted to engage said slot to lock the parts in position.

4. A bench plane bit clamping means comprising a bed, a blade, a spring plate, having a central screw-threaded aperture, a locking bolt having a threaded portion engaging said threaded aperture, said bolt extending through said blade and bed and having a slot in its lower end, and a pawl pivoted to the underside of said bed adapted to engage the slot in said bolt to lock the parts in their adjusted position.

5. A bench plane bit clamping means comprising a bed, a blade, a spring plate having a central screw-threaded aperture, a locking bolt having a threaded portion engaging said threaded aperture, said bolt extending through said blade and bed and having a slot in its lower end, a pawl pivoted to the

under side of said bed, and a finger carried by said pawl adapted to engage the slot in said bolt for locking the parts in their adjusted positions.

5 6. In a bench plane bit clamping means, the combination with a bed and a blade, of a bolt extending through said blade and bed having a slot in its lower end, springs means

interposed between the head of said bolt and blade and means carried by said bed adapted to engage the slot of said bolt for locking 10 the parts in position.

Signed at New York, in the county of New York and State of New York, this 3rd day of April A. D. 1924.

JOHN SZAKO.
